UNITED STATES PATENT OFFICE.

GEORGE LESTER WILLIAMS, OF SOUTH ORANGE, NEW JERSEY, ASSIGNOR TO GEORGE LESTER WILLIAMS, OF SOUTH ORANGE, NEW JERSEY, AND TRUDE F. STEWART, OF PASADENA, CALIFORNIA.

BUILDING CONSTRUCTION.

Application filed February 24, 1923. Serial No. 620,957.

To all whom it may concern:

Be it known that I, GEORGE LESTER WILLIAMS, a citizen of the United States, residing in South Orange, in the county of Essex and State of New Jersey, have invented an Improvement in Building Constructions, of which the following description, in connection with the accompanying drawings, is a specification, like characters on the drawings representing like parts.

This invention relates to a building construction and particularly to a substantially monolithic ceiling composed of a precast slab of gypsum or like plastic material.

The invention has for its object to provide a superior precast ceiling slab with which the substantially monolithic ceiling may be formed, which is constructed so as to be suspended from the metal floor frame of the building, which can be placed in position in a minimum time, which cooperates with adjacent slabs to form a flush ceiling, which efficiently protects the metal floor frame from fire below the same and which provides for a plastic key for the plaster coat applied to its under surface.

To this end, the ceiling slab is constructed as will be hereinafter described. The particular features of the invention will be pointed out in the claims at the end of this specification.

Fig. 1 represents a sufficient portion of a building embodying this invention to enable it to be understood;

Fig. 2, a view in section and elevation of a portion of the structure shown in Fig. 1;

Fig. 3, a plan of a precast ceiling slab shown in Figs. 1 and 2;

Fig. 4, a detail in section of two adjacent ceiling slabs with the plaster coat applied thereto;

Fig. 5, a side elevation of a portion of the ceiling slab shown in Fig. 3;

Fig. 6, a plan of a modified form of ceiling slab; and

Fig. 7, a detail in section on the line 7—7, Fig. 6.

In Fig. 1 is represented a portion of the metal floor frame of a building which is provided with precast ceiling slabs of gypsum or like material embodying this invention.

The floor frame comprises metal girders *a*, only one of which is shown, and metal beams *b* which are supported at their ends

by said girders and only two of which are shown.

The metal beams *b* are herein shown as channel bars and in accordance with this invention, they support ceiling slabs *c*. The ceiling slabs *c* are precast and are composed of gypsum or like plastic material and each slab is preferably provided with a metal reinforcement, herein shown as a series of metal rods or bars 10.

The ceiling slabs *c* are provided with anchoring devices 12 by means of which the slabs may be suspended from the beams *b*. The anchoring devices 12 may be of any suitable construction and in Figs. 1, 2 and 3 are shown as hooks, whose lower ends are embedded in the slab *c* and preferably engaged with the metal reinforcement 10 therein, whereas in Figs. 6 and 7 the anchoring devices 12 are shown as metal strips which are folded to form a loop 13 above the slab and arms 14 within the slab.

In the present instance, the anchoring devices 12 are engaged by wires or rods 15, 16, which are engaged with a metal clip 17 extended over the top of a beam *b*.

The metal clips 17 are placed upon the beam *b*, and the slab *c* can be lifted by the wires or rods 15, 16 whose ends are engaged with the clips. In the present case, the free end of the wire 15 may be passed through a hole 18 in the clip 17 and then bent to prevent disengagement from the clip, and the free end of the wire 16 may be bent to form a hook 19 which engages a link 20 whose upper end is engaged with an arm 21 on the clip before said arm is pressed against the under side of the upper flange of the beam.

The anchoring devices are located with relation to the ends of the slab, so that a portion of the ends of two adjacent slabs are located below the lower surface of the beam and preferably contact, so that the bottom of the beam is protected against fire by the adjacent slabs, which are of substantial thickness.

To still further protect the bottom of the beam from fire, provision is made for sealing the joint between the end walls of adjacent slabs, and to this end the ceiling slab *c* is provided at one end with a rabbet 22 which is formed in the upper surface thereof and is made wide enough to extend beyond the bottom surface of the beam when

the slab is in its operative position, as clearly shown in Fig. 2.

By reference to Fig. 2, it will be seen that when two adjacent slabs have been secured 5 to the beam with their adjacent ends under the bottom surface thereof, a portion of the rabbet 22 in one slab will be open or uncovered by the beam, which permits grout or gypsum 23 in a more or less fluid or plastic 10 condition to be poured into the rabbet and fill the space between the ends of the slabs and also fill the rabbet, and thus seal the joint between the ends of the slabs and most effectively protect the bottom surface of the 15 beam from fire below the beam. Provision is also made for enabling the rabbeted end of the slab to be quickly positioned and yet have its lower surface flush with the under surface of the adjacent slab, and to this end, 20 the rabbeted end of the slab is provided with one or more projections or stops 24, herein shown as two in number and located near the opposite sides of the slab. The stops 24 have their upper surface level with the upper surface 25 of the slab, so that, when the slab is lifted into position with its rabbeted end below the beam, the stops 24 will engage the bottom surface of the beam and thereby place the bottom surface of its slab flush 30 or substantially flush with the bottom surface of the adjacent slab.

It will thus be seen that the slabs can be quickly and easily placed in position with their under surfaces flush or substantially 35 flush and delicate adjustment of the slabs by the hangers or suspending wires 15, 16 is avoided.

The slabs *c* are provided on their sides with ribs 25 located below the upper surface 40 and near the lower surface and preferably provided with beveled upper and lower surfaces 26, 27. The side ribs 25 of adjacent slabs are designed to contact as represented in Fig. 4, and cooperate to form an open 45 slot between the upper portion of the sides of adjacent slabs for the reception of grout or plastic material 28, which fills said slot and cooperates with the side ribs to seal the joint between the sides of adjacent slabs and 50 form a fire stop between the sides of adjacent slabs.

The beveled lower surfaces 27 of cooperating side ribs 25 form a slot below the side ribs for the reception of a key 29 of plastic 55 material which serves to bond the plaster coat 30 to the slabs, and also cooperates with the side ribs and the grout 28 to form the fire stop between the sides of adjacent slabs.

From the above description and by reference 60 to the drawing, it will be seen that the floors of a building may be provided with a ceiling composed of precast slabs of gypsum or like plastic material with a minimum labor and in a minimum time, and that when 65 said slabs have been erected in place and

their joints grouted and sealed, a continuous or substantially monolithic ceiling is formed which effectively protects from fire the metal framework of the floor above the ceiling, and also effectively stops the fire from passing through the portion of the ceiling between the metal members of the floor frame. 70

In Figs. 1 and 2, is also shown precast slabs 31 of gypsum or like plastic material which rest upon the beams and form a floor 75 of the building.

One embodiment of the invention is herein shown, but it is not desired to limit the invention to the particular construction shown. 80

The anchoring devices 12 are embedded in the slab preferably with their lower ends a substantial distance above the bottom of the slab so as to be protected against fire by a substantial thickness of gypsum or like plastic material. 85

Claims:

1. A precast slab of plastic material having its upper surface provided at one end with a rabbet and with a projection extended 90 from the bottom of said rabbet with its upper surface substantially flush with the upper surface of said slab.

2. A precast slab of plastic material having its upper surface provided at one end with a rabbet and with a projection extended from the bottom of said rabbet with its upper surface substantially flush with the upper surface of said slab, and having its sides provided with ribs located below the 100 upper surface of said slab.

3. A precast slab of plastic material having its upper surface provided at one end with a rabbet and with a projection extended from the bottom of said rabbet with its 105 upper surface substantially flush with the upper surface of said slab, and having its sides provided with ribs located below the upper surface of said slab and provided with a beveled under surface to form a key slot 110 with the side rib of a cooperating slab.

4. In a building construction, in combination, a metal floor frame having members spaced apart, a substantially monolithic ceiling suspended from said floor frame, and composed of a plurality of precast slabs of plastic material having the ends of adjacent slabs extended under a member of the floor frame and having side ribs located below the upper surface of said slabs, plastic material interposed between the floor member and one of the slabs thereunder and sealing the joint between the ends of the adjacent slabs under said floor member, and plastic material between the sides of adjacent slabs and above the side ribs thereof to seal the joint between the sides of adjacent slabs. 120

5. In a building construction, in combination, a floor frame having members spaced apart, a substantially monolithic ceiling hav- 125

ing a substantially flat under surface located below said floor frame and composed of a plurality of precast slabs of plastic material provided with metal reenforcements spanning the distance between two floor members, and means connected with the reenforcement of the slabs at the opposite ends of the latter and with the upper portion of said floor members to suspend the ceiling slabs from 10 said floor members.

6. In a building construction, in combination, a floor frame provided with a plurality of floor members spaced apart and forming bays, and a continuous flat ceiling located below and suspended from said floor members comprising a plurality of precast slabs of plastic material of substantial thickness and arranged with each slab spanning the bay between two of the floor members, each of 15 the slabs being suspended at each of its ends only from a floor member and cooperating with the other slabs to form an effective fire-proofing for the floor members.

7. In a building construction, in combination, a floor frame provided with a plurality of floor members spaced apart and forming bays, and a continuous flat ceiling located

below and suspended from said floor members and comprising a plurality of precast slabs of plastic material of substantial thickness and arranged with each slab spanning the bay between two floor members and with the ends of each slab terminating in proximity to a floor member, and devices 30 operating with the reenforcement within said slabs near each end thereof for directly suspending the slab from the floor members immediately above each end of the same.

8. In a building construction, in combination, a floor frame provided with a plurality of floor members spaced apart and forming bays, a continuous flat ceiling located below and suspended from said floor members comprising a plurality of precast slabs of plastic material of substantial thickness and arranged with each slab spanning the bay between two of the floor members, and means 40 connecting the longitudinal reenforcement within the slab directly to the floor beams 45 near the opposite ends of the slab.

In testimony whereof I have signed my name to this specification.

GEORGE LESTER WILLIAMS.
